UNITED STATES PATENT OFFICE.

MORRIS ROSENFIELD AND CLAUDE WHITE, OF NEW YORK, N. Y.

SPRING-HANDLE.

1,203,272.

Specification of Letters Patent.

Patented Oct. 31, 1916.

Application filed February 24, 1916. Serial No. 80,141.

To all whom it may concern:

Be it known that we, MORRIS ROSENFIELD and CLAUDE WHITE, citizens of the United States, and residents, respectively, of the boroughs of Manhattan and Brooklyn, city of New York, and State of New York, have invented new and useful Improvements in Spring-Handles, of which the following is a specification.

10 This invention relates to improvements in spring handles and is especially adapted for use for carrying packages, suit cases and the like.

By the use of our invention we produce 15 a handle comprising a spring having a primary spiral coil and secondary reverse coils, the preferred embodiment of our invention being formed of a single strand of wire having the primary spiral coil formed at its center, the reverse coils beginning at the opposite ends of the primary coil with the ends thereof abutting each other at the center of the primary coil and the handle having at each end of the spring a hook formed of 20 both strands of the wire formed intermediate the primary and secondary coils, so that an equal pull will be exerted on the primary and reverse coils from opposite ends of the handle when the same is attached to 25 a package or other load. In said preferred embodiment we preferably provide a seat for the spring comprising a cylindrical steel casing arc-shaped in longitudinal conformation, a spring of the character hereinabove described within said casing with the hooks extending upon the outside thereof at opposite ends, and said casing is then covered with leather or other suitable material according to the use for which the 30 handle is to be employed.

Referring now to these drawings in which similar reference characters designate corresponding parts throughout the several views, Figure 1 illustrates in side elevation 35 a portion of a strand of wire so spirally coiled as to form a portion of the primary coil of our improved handle; Fig. 2 is a similar view of a wire strand spirally coiled at one side to illustrate both the primary and secondary, reverse windings together 40 with the intermediate double-strand hook, and at the other side said strand being coiled to illustrate the primary coil only, spaces being left for the secondary, reverse 45 coil. Fig. 3 is a longitudinal section of a handle embodying our invention and illus-

trating our double wound spring seated within an arc-shaped, cylindrical casing having a covering of flexible material; Fig. 4 is a perspective view of one end of our 60 double-wound spring illustrating the double-strand hook and the beginning of the reverse coil at one side; and Fig. 5 is a section on the line 5—5 of Fig. 3.

Referring now to these drawings, 1 indicates a strand of wire which is initially spirally coiled, preferably at its central portion, to provide what we shall term a primary coil which as shown is of such open construction or has its rings or windings 2 65 so relatively spaced as to permit the seating between the windings of the primary coil of the windings 3 of a secondary or reverse coil or coils. Preferably the secondary, reverse coils are wound or woven in 70 between the strands 2 of the primary coil after the formation intermediate the primary and secondary, reverse coils of a double-strand hook 4 formed at opposite ends 75 of the spring handle.

In the preferred embodiment of our invention the spring handle is seated within a cylindrical casing 5, preferably stamped up out of sheet metal, and bent longitudinally in the form of an arc or crescent. This 80 casing 5 is preferably provided with a covering 6 of leather or similar material, and the hooks 4 extend on opposite sides of said covered casing.

Obviously a handle of the character hereinabove described will, when employed to carry a load as, for example, a suit-case or trunk, take up and compensate for strains or shocks which may occur in the course of carrying the load.

Having described our invention, we claim:

1. A spring comprising a primary spiral coil having its windings suitably spaced and a secondary coil of similar diameter having its windings seated between and intermeshing with the windings of the primary coil and connecting means for the said coils adapted to cause any exterior stress to be applied to both coils simultaneously.

2. A spring comprising a single strand of wire bent to provide a primary spiral coil having its windings suitably spaced, a secondary coil having its windings located between the windings of the primary coil and hooks at opposite ends of said spring.

3. A spring comprising a single strand of wire having a primary coil formed from its

central portion and secondary coils formed on opposite sides of the primary coil and coiled in opposite directions toward the center of the primary coil, said secondary coils having their windings seated between and intermeshing with the windings of the primary coil.

4. A spring comprising a single strand of wire having a primary coil formed from its central portion, secondary coils formed on opposite sides of the primary coil and coiled in opposite directions toward the center of the primary coil, said secondary coils having their windings seated between and intermeshing with the windings of the primary coil and hooks at opposite ends of said spring formed by doubling the strand intermediate the primary and secondary coils.

5. A spiral spring arc-shaped in conformation comprising a single strand of wire having a primary coil formed from its central portion, secondary, reverse coils formed on opposite sides of the primary coiling and coiled in opposite directions toward the center of the primary coil, said reverse coils having their windings seated between and intermeshing with the windings of the primary coil and hooks at opposite ends of said spring formed by doubling the strand intermediate the primary and reverse coils.

6. A metallic casing cylindrical in cross section and arc-shaped in longitudinal conformation, a covering of leather or like material for such casing, a spiral spring seated within said casing having attaching means extending without the casing on opposite sides.

7. A spiral spring formed of a single strand of wire having a primary coil formed from its central portion, reverse coils formed on opposite sides of the primary coil and coiled in opposite directions toward the center of the primary coil, said reverse coils having their windings seated between and intermeshing with the windings of the primary coil and hooks at opposite ends of said spring formed by doubling the strand intermediate the primary and reverse coils, a casing of rigid material within which said spring is seated having the hooks extending on opposite sides thereof and a suitable flexible covering for said casing.

In witness whereof, we have signed our names to the foregoing specification in the presence of two subscribing witnesses.

MORRIS ROSENFIELD.
CLAUDE WHITE.
